UNITED STATES PATENT OFFICE.

GEORGE FRANCIS READ, OF LONDON, ENGLAND, ASSIGNOR TO R. HOE AND CO., OF NEW YORK, N. Y., A CORPORATION OF NEW YORK.

PRINTING-CYLINDER.

1,179,559.

Specification of Letters Patent. Patented Apr. 18, 1916.

Application filed February 2, 1910. Serial No. 541,448.

To all whom it may concern:

Be it known that I, GEORGE F. READ, a citizen of the United States, residing at London, county of Middlesex, England, have invented certain new and useful Improvements in Printing-Cylinders, fully described and represented in the following specification and the accompanying drawings, forming a part of the same.

10 This invention relates to certain improvements in printing cylinders.

The object of the invention is to provide a rapid, convenient and efficient means for varying the position of the cylinders in a 15 printing machine by adjusting devices which may be simultaneously operated and are so positioned that the adjustments may be effected while the machine is running.

Referring to the accompanying drawings—Figure 1 illustrates in end view one 20 of the cylinders of a printing machine having adjusting devices constructed in accordance with the invention applied thereto. Fig. 2 is a section on the line 2—2 of Fig. 1. Fig. 3 is a plan view of the construction shown in Fig. 1. Fig. 4 is a section on the line 4—4 of Fig. 1.

In the drawings, 1 represents one of the cylinders of a printing machine, the shaft 30 2 on which the cylinder is mounted being supported in a bushing 3 mounted in bearing blocks 4, these bearing blocks fitting in recesses 5 in the frame of the machine, as is usual in such constructions.

35 Constructions embodying the invention will include devices for adjusting the position of the bearing blocks in order to vary the position of the cylinder. As shown, the lower part of the bearing box rests on the 40 enlarged head 6 of an adjusting screw 7, the screw being tapped into an opening 8 in the bottom of the recess 5.

In the particular construction shown, a second adjusting screw 9 having a bearing 45 head 10 is tapped through an opening 11 in a block 12, this block being secured to the frame in any suitable manner, as by screws 13, 14, this block serving as a cap or cover for the recess in the frame.

50 In the best constructions embodying the invention, one of the adjusting devices—in the construction shown, the screw 9—will bear against a wear plate or block 15 removably secured in one of the bearing

blocks 4 in any suitable manner, as by 55 screws 16.

Constructions embodying the invention will include means for simultaneously actuating the adjusting devices. While these means may be varied, in the construction 60 illustrated there is provided an actuator shaft 17, this shaft passing through an opening in the bearing blocks and also through an opening in the boss 18 formed in one piece with the cover block 12. This 65 shaft, in the construction shown, carries small gears 19, 20, the gear 19 meshing with a gear 21 on the screw 9 and the gear 20 meshing with a gear 22 on the screw 7. It will be observed that this shaft is partly 70 contained within the recess in which the bearing is located, thus making the construction exceedingly compact. This actuator shaft may be operated in various ways. In the construction shown, it is provided 75 with a perforated head 23 in which a pin or "tommy" may be inserted to turn the shaft. It is obvious that as the shaft is rotated the cylinder bearing, shaft and cylinder will be adjusted, and it is also obvious 80 that the actuator shaft is located in such a manner as to be readily accessible notwithstanding the gearing (not shown) which is ordinarily employed for driving the cylinders. It is further clear that any adjustments necessary may be effected while the 85 cylinder is in operation. It will be understood, of course, that similar adjusting devices are provided on each end of the cylinder, but as they are duplicates only one is 90 shown.

Changes and variations may be made in the construction by which the invention is carried into effect. The invention is not, therefore, to be confined to the particular 95 construction herein shown and described.

What is claimed is:—

1. In a printing machine, the combination with a frame having recesses for the cylinder bearings, of bearings in said recesses, an impression adjusting means for each bearing located on opposite sides thereof, said means including an actuator shaft for each bearing, said shaft being partly contained within the recess in which the bearing it adjusts is contained. 100

2. In a printing machine, the combination with a frame having a recess for the

cylinder bearings, of bearings in said recesses, an actuator shaft for each bearing partly contained within the recess for the bearing, and gear operated impression adjusting means for each bearing located on opposite sides thereof operated by the shafts.

3. In a printing machine, the combination with a frame having recesses for the cylinder bearings, of bearings in said recesses, upper and lower gear operated adjusting screws for the bearings, vertical actuator shafts partly contained within the recesses in which the bearings are mounted, gears on the shafts for operating the adjusting screws, and covers for the bearings through which the shafts extend.

4. In a printing machine, the combination, with a cylinder, of a frame having a recess, a bearing slidable in said recess and arranged to support the cylinder, a pair of vertical impression adjusting screws arranged to act on opposite sides of the bearing, an actuator shaft partly contained with-

in the recess within which the bearing is mounted, and gearing between the said actuator shaft and each adjusting screw.

5. In a printing machine, the combination, with a cylinder, of a frame having a recess, a bearing slidable in said recess and arranged to support the cylinder, a cover for the bearing, a pair of vertical impression adjusting screws arranged to act on opposite sides of the bearing, an actuator shaft partly contained within the recess within which the bearing is mounted, and extending through said bearing-cover, and gears connecting the actuator shaft to each adjusting screw.

In testimony whereof, I have hereunto set my hand, in the presence of two subscribing witnesses.

GEORGE FRANCIS READ.
